UNITED STATES PATENT OFFICE.

LESLIE STEVENS, OF GLEN RIDGE, NEW JERSEY.

SECTIONAL FORMING-BLOCK.

1,109,713.

Specification of Letters Patent.

Patented Sept. 8, 1914.

Application filed May 14, 1909. Serial No. 495,898.

To all whom it may concern:

Be it known that I, LESLIE STEVENS, a citizen of the United States, residing at Glen Ridge, county of Essex, and State of New Jersey, have invented certain new and useful Improvements in Sectional Forming-Blocks, fully described and represented in the following specification and the accompanying drawings, forming a part of the same.

10 This invention relates to sectional forming blocks, for forming hats, shoes and various other articles where the opening to the interior of the completed article is too small to permit the forming block to be withdrawn.

15 It is customary in forming such articles to make use of sectional blocks formed of sections each of which is smaller than the opening to the interior of the completed article and which are adapted to be withdrawn successively after the article has been formed on the block.

The present invention aims to provide an improved sectional block having means whereby the sections of the block will be held securely together and relative movement thereof will be prevented under ordinary working strains and conditions, and which securing means will permit the sections of the block to be readily separated when desired and successively withdrawn from the interior of an article which has been formed on the block. Various means have been resorted to heretofore for holding the sections of such blocks together while in use, but such means have been unsatisfactory for various reasons. Dove-tailed ribs and grooves on the abutting faces of the sections have been quite commonly used for this purpose, but are unsatisfactory because of the difficulty of getting a fit which is neither too loose, so that the sections are not kept together, or too tight so as to cause difficulty in assembling the sections, as well as in separating them. As forming blocks of various kinds are commonly made of wood, the dove-tailed joints are also liable to swell and make it difficult, if not impossible, to separate the sections. Such difficulties and other difficulties heretofore met with in the attempt to provide a practical sectional block are overcome by the present invention, while at the same time the cost of construction is less than for the dove-tailed constructions which have been heretofore very generally in use.

The invention consists in certain novel

features of construction and combinations of parts, all as fully hereinafter described and specifically pointed out in the claims.

The invention has been made especially 60 with the idea of providing an improved hat block, but it will be understood that features of the invention may be applied to all kinds of forming blocks to which they may be found adaptable.

65 In the accompanying drawings, forming part of this specification, and which show a hat block embodying the various features of the invention in the preferred form:—Figure 1 is a plan view of the base of the 70 block with the steady plate or hub removed. Fig. 2 is a side view partly in section showing the block with its base or outer face uppermost. Figs. 3 and 4 are sections on lines 3 and 4 respectively of Fig. 1. Fig. 5 75 is a broken sectional view taken on line 3 of Fig. 1, but showing the medial section of the block partly withdrawn. Fig. 6 is a plan view of the steady plate. Figs. 2 to 5 show the steady plate attached. 80

85 Referring to the drawings, the hat block, as shown, is intended for forming hat crowns which have parallel sides and a head opening of less diameter than the crown, such smaller head opening being formed by folding the felt or other material of which the hat is formed inward from the base of the crown and then outward to the brim, as indicated by dotted lines in Fig. 2. The block might, of course, be of any desired 90 shape, according to the shape of the hat crown to be formed. The invention relates 95 in one of its features, however, especially to blocks for forming hats having a head opening smaller than the base of the crown. The 100 block is of the usual five-section construction, having a medial section 10, two side sections 11 lying against opposite sides of the section 10 and extending beyond said section in either direction, and two oppositely arranged sections 12 adjacent to the remaining sides of the section 10 and between the extended portions of the side sections 11. The exterior surfaces of the side sections 11 and 12 are formed to produce a 105 block of the desired shape when the sections are assembled as shown in Figs. 1 to 4, and the medial section may be provided with the usual finger holes 13 and central spinner or chuck hole 14. The meeting faces of the 110 block sections are plain faces, and the medial section 10 is formed with its four side faces

sloping slightly inward from the base, and the corresponding faces of the side sections are correspondingly inclined, so that the medial section may be more readily moved into place and withdrawn. The medial section 10 has in each of its four side faces a vertical slot or recess 15 in which is set a catch 16 which is adapted to engage a pin or keeper 17 on the adjacent side section.

10 The catches 16 are preferably formed of metal plates pivotally mounted in the recesses 15, as by means of pivot pins 18 set in grooves 19 and held in place by having one or both ends bent and driven into the body of the section 10, as indicated by dotted lines in Fig. 1. Each of the catch plates is formed with an inside notch 20 beyond the pivotal point of the plate adapted to engage the pin or keeper 17 of the adjacent side section, and each plate has beyond the notch an extension 21 having an inclined inner edge, and each plate is under spring tension to hold it normally in the position of the plates shown in Figs. 3 and 5. To provide such spring tension, the inner ends of the catch plates on opposite sides of the block section 10 are connected by means of coiled tension springs 22 lying in openings or bores 23 extending through the block section from side to side. The inner faces of the side sections 11 and 12 of the block are formed with grooves 24 in position to register with the grooves 15 of the section 10 and to receive the outer portions of the catch plates 16. The grooves 15 and 24 are preferably made of a width corresponding to the thickness of the catch plates and so as to receive the catch plates with an easy fit, and the catch plates are made of sufficient length and width so that in addition to their function of securing the sections of the block together, they will also act to hold the sections against relative turning movement.

When the sections of the block are to be assembled, the side sections 11 and 12 are first brought into proper relative position, and the central section 10, which is the last to be inserted, or the last placed section of the block, is then inserted between the side sections and pushed down into place, as shown in Figs. 1 to 4. As the section 10 is pushed into place, the inclined edges of the extensions 21 of the catch plates will engage the pins 17 and will cause the catch plates to be swung outward; and then as the section 10 comes to its proper place the shoulders below the notches 20 will have passed below the pins 17 and the catch plates will snap inward under tension of their springs 22. They will then hold the sections of the block together under all ordinary working conditions, the springs 22 being sufficiently strong to prevent the side sections from being drawn away from the central section under such strains as will come

on the block in its ordinary use, and the catches also serving to prevent relative movement between the central block and the side blocks in a direction parallel to their meeting faces under ordinary working strains.

In order that the central section may be readily removed when desired, the shoulder forming the lower edge of the notch 20 of each of the catch plates is inclined so that under the influence of a strong pull on the central section in the direction of the arrow in Fig. 5, the catch plates will be swung outward by the engagement of such inclined edge of the notches 20 with the pins 17 and the central section thereby released from the side sections, so that it may be readily withdrawn, as indicated in Fig. 5.

While the catch plates may be depended upon for preventing relative turning movement of the connected sections of the block when formed as shown and as above described, yet it is sometimes desirable to provide means for holding the assembled sections of the block more steadily together and especially for preventing any turning movement whatever of the side sections 11. For this purpose steady guides may be provided, as shown at 30 in Fig. 1, such guides being formed by plates set into the face of the block 10 and adapted to fit in slots cut in the faces of the blocks 11. Preferably, however, or in combination with the guides 30, I provide for this purpose a steady plate 35 formed on or secured to the top or outer face of the central, or last placed section 10 and of sufficient size to extend over a portion of the tops of the side sections of the block. When the sections of the block are assembled with the side sections secured to the central section by the spring catches, the tops of the side sections will come close up against the plate 35 and will be thereby held steadily in position and prevented from shifting or turning relatively to the central section. The plate 35 also serves as a forming shoulder or hub for determining the shape and size and position of the head opening of hats which are formed with an inward fold from the base of the crown as indicated by dotted lines in Fig. 2. By making such forming hub removable from the section 10 of the block, as by making it of a separate piece secured to the section 10 by means of screws 36, the same block may be provided with a number of forming hubs of different sizes and forms and so be adapted for forming hats of the style above referred to having head openings of different sizes and forms. A forming shoulder or hub might also be provided on a block otherwise than by means of a plate forming part of or secured to the central, or last placed, section of a sectional block. This

feature of the invention of providing a block with a top plate or hub, whether it is intended to serve as a forming hub or as a steadyng device for the block sections, or to perform both such functions, is not limited to use in blocks embodying other features of the invention, but may be employed generally in all blocks to which it may be found adaptable.

10 It will be seen that by the use of the securing and steadyng devices as above described, block sections having plane meeting faces may be securely and firmly held together under normal working conditions, and readily separated when desired for successive removal from the hat or other article which has been formed.

15 It is to be understood that the invention is not to be limited to the exact construction shown and to which the foregoing description has been mainly confined, but that it includes changes and modifications thereof within the claims.

What is claimed is:

20 1. A forming block formed of a plurality of sections, and having a spring catch carried by one of the block sections in position to engage a co-acting member on an adjacent block section when the sections are assembled, said catch being formed to hold said block sections against relative separating movement in a direction either transverse to their meeting faces or parallel thereto under ordinary working strains, and 25 said catch and co-acting member being formed to cause the catch to move against its spring to free said sections one from the other under the influence of a strong pull tending to move one of the block sections 30 relatively to the other in a direction substantially parallel to their meeting faces.

25 2. A forming block formed of a plurality of sections, and having a spring catch carried by one of the block sections in position to engage a co-acting member on an adjacent block section when the sections are assembled to hold said sections against relative separating movement in a direction either transverse to or parallel to their meeting faces, said catch being formed by a metal plate pivotally mounted in a slot in the block section by which it is carried in position to project edgewise to enter a slot in the adjacent block section to prevent relative turning movement between said block sections.

30 3. A forming block formed of a plurality of sections provided with releasable holding means for holding adjoining block sections against relative separating movement in a direction either transverse to or parallel to their meeting faces comprising a plate having an inside notch and mounted edgewise in a slot in the meeting face of one section and projecting therefrom to en-

ter a slot in the meeting face of the adjoining section and a member carried by said adjoining section to co-act with said plate to hold said sections against relative separating movement.

4. A forming block formed of a plurality of sections provided with holding means for holding adjoining block sections against relative separating movement in a direction either transverse to or parallel to their meeting faces comprising a plate mounted edgewise in a slot in the meeting face of one section and projecting therefrom to enter a slot in the meeting face of the adjoining section and a member carried by said adjoining section to co-act with said plate to hold said sections against relative separating movement, said plate having an inside notch and an extension beyond the notch with an inclined inside edge, and one of said parts being yieldingly held and said parts being formed to cause the yieldingly held part to move to free said block sections one from the other under the influence of a strong pull tending to move one of the sections relatively to the other in a direction substantially parallel to their meeting faces.

5. A forming block formed of a plurality of sections provided with holding means for holding adjoining block sections together comprising a plate mounted edgewise in a slot in the meeting face of one section and projecting therefrom to enter a slot in the meeting face of the adjoining section and a member carried by said adjoining section to co-act with said plate to hold said sections against relative separating movement in a direction either transverse to or parallel to their meeting faces, and steadyng means other than said holding means for preventing relative turning movement between said block sections.

6. A sectional forming block formed of a medial section and a plurality of marginal sections, and having holding means for holding the marginal sections to the medial section and for preventing the medial section from being withdrawn from the marginal sections under ordinary working strains, said holding means comprising plates mounted edgewise in slots in the meeting faces of the medial section and projecting therefrom to enter slots in the meeting faces of the marginal sections and members carried by the marginal sections to co-act with said plates to prevent relative separating movement between the medial section and the marginal sections in a direction either transverse to or parallel to their meeting faces.

7. A forming block formed of a plurality of sections provided with holding means for holding adjoining block sections together comprising a spring catch formed by a

- metal plate pivotally mounted in a slot in the meeting face of one of the block sections and projecting therefrom to enter a slot in the meeting face of the adjoining section, 5 said plate being formed with an inside notch 20 and with an extension 21 beyond the notch having an inclined inner edge and being under spring tension to move its notched end inward, and a pin or keeper 17 10 in the slot in said adjoining block section in position to be engaged by the notch of the catch plate.
8. A sectional forming block formed of a medial section, and a plurality of marginal 15 sections, and having holding means for holding the marginal sections to the medial section and for preventing the medial section from being withdrawn from the marginal sections under ordinary working strains, and 20 having shoulders extending from the medial section in position to bear on the bases of the marginal sections, said holding means being adapted to yield under the influence of a 25 strong withdrawing pull on the medial section to permit the medial section to be withdrawn.
9. A sectional forming block formed of a medial section, and a plurality of marginal sections, and having spring catches for holding 30 the sections together when assembled, and a steady plate secured to the base of the medial section and extending outward therefrom to bear on the bases of the marginal sections.
- 35 10. A sectional forming block formed of a medial section and a plurality of marginal sections, and having means for holding the sections together when assembled, and a steady plate secured to the base of the medial section and extending outward therefrom to bear on the bases of the marginal sections.
- 40 11. A sectional forming block for forming the crowns of hats which have a head opening smaller than the base of the crown, formed of a medial section, and a plurality of marginal sections, and having holding means for locking the sections together adapted to yield to permit the medial section 45 to be withdrawn, and a plate on the base of

the medial section and extending outward therefrom to bear on the bases of the marginal sections and the periphery of which provides a forming shoulder for determining the size and shape of the head opening of 55 the hat.

12. A sectional forming block for forming the crowns of hats which have a head opening smaller than the base of the crown, formed of a medial section, and a plurality 60 of marginal sections, and having a plate secured to the base of the medial section and extending outward therefrom to bear on the bases of the marginal sections and the periphery of which provides a forming shoulder for determining the size and shape of 65 the head opening of the hat.

13. A sectional forming block for forming the crowns of hats which have a head opening smaller than the base of the crown, 70 formed of a medial section, and a plurality of marginal sections, and having a forming shoulder for determining the size and shape of the head opening of the hat formed by a part removably secured to the base face of the medial block section and extending outward to bear on the bases of the marginal sections.

14. A forming block for forming the crowns of hats which have a head opening 80 smaller than the base of the crown, having on its base face a forming shoulder set in from the edge of the base face of the block for determining the size and shape of the head opening of the hat.

15. A forming block for forming the crowns of hats which have a head opening smaller than the base of the crown, having removably secured to its base face a part 90 the periphery of which provides a forming shoulder set in from the edge of the base face of the block for determining the size and shape of the head opening of the hat.

In testimony whereof, I have hereunto set my hand, in the presence of two subscribing 95 witnesses.

LESLIE STEVENS.
